METHOD OF MAKING ELASTIC YARN

Fayette D. Chittenden, Rumford, and Kenneth J. Rupprecht, Barrington, R. I., assignors to United States Rubber Company, New York, N. Y., a corporation of New Jersey

Application February 11, 1939, Serial No. 255,912

8 Claims. (Cl. 57—163)

This invention relates to improvements in the method of and apparatus for making a balanced elastic yarn consisting of a twisted rubber core having a single cover of textile fibers spun about the core in a direction to cause the helical windings of the cover to balance the twists of the rubber core.

In making such an elastic yarn it is necessary first to twist the bare rubber core, after which the cover is spun thereupon in the opposite direction. Approximately fifty per cent of the twist imparted to the bare rubber core is or may be removed as the cover and core are spun together to wind the cover about the core. Therefore it is necessary to impart a relatively high number of twists per inch to the rubber core preparatory to spinning the cover thereupon, and the cost of pretwisting this rubber core unless performed at high speed and under the most favorable conditions may constitute a substantial part of the cost of producing such elastic yarn.

The elastic yarn above described and one method of making the same is fully disclosed and claimed in the Boutwell H. Foster Patent No. 2,024,156 granted December 17, 1935. But in this, Foster patent the bare rubber core is described as having been previously twisted and wound onto a spool from which it is supplied to the mechanism for spinning a cover thereupon.

One important feature of the present invention resides in the method of an apparatus for pretwisting the bare rubber core and then spinning the cover thereupon all in a continuous operation.

In order that the finished elastic yarn herein contemplated may be well balanced and uniform in construction and stretch characteristics it is important to avoid the occurrence of variations in the stretch of the rubber core at certain stages during the formation of the elastic yarn. This is particularly true with respect to the operation of pretwisting the rubber core, because variations in the stretch of the rubber core at this time will change greatly the number of twists per inch imparted thereto.

Another important feature of the invention therefore resides in feed means for drawing the rubber thread endwise from the rotating let-off package at a definite speed to thereby impart to this thread a predetermined number of twists per inch for a given percentage of stretch, and a further feature resides in the construction whereby the operation of this feed means at a definite speed ratio to the nip rolls of the spinning mechanisms to which the rubber thread is delivered

serves accurately to control the tension of this thread at the instant it is being delivered to the spinning point.

In carrying out the present invention it is contemplated that the let-off package for the rubber thread, which is rotated as the thread is drawn endwise therefrom to twist the thread, may be supported in various positions as the thread is drawn therefrom. For example it is contemplated that the thread may be drawn downward from the package in the direction of gravity, or upwardly therefrom against the force of gravity, or at angles to these positions.

One of the more specific features of the invention therefore resides in the arrangement whereby the rubber thread travels in a general downward direction from the time it leaves the rotating supply package until the cover is spun thereupon and the yarn is wound on the take-up package.

Other features of the invention and novel combination of parts in addition to the above will be hereinafter described in connection with the accompanying drawings which illustrate good practical forms of the invention.

In the drawings:

Fig. 1 is a conventional diagrammatic view with parts in section of one form of mechanism for carrying out the invention;

Fig. 2 is an enlarged side view of an elastic yarn formed upon the apparatus of Fig. 1 and comprising an elastic core and a cover wound helically thereupon;

Fig. 3 is a top view of the motor brake mechanism of Fig. 1;

Fig. 4 is a view similar to Fig. 1 showing a modification thereof; and

Fig. 5 is a similar view showing a further modification of Fig. 1.

The present invention was developed primarily for the manufacture of fine elastic yarns having a core as fine as 75's or finer, although the invention may be employed to manufacture elastic yarns having a larger core. A large number of twists per inch must therefore be imparted to this fine rubber thread before the cover is spun thereupon, and the number of twists may be as high as 200 per inch or higher. It is therefore important that the mechanism provided to impart this twist to the fine rubber thread shall operate at high speed in order to give a reasonably high production of elastic yarn per covering unit.

The bare elastic thread 10 forming the core of the elastic yarn may be formed of rubber or other

rubberlike material having the desired stretch characteristics. This thread which is to be twisted, or what may be called pre-twisted, is preferably wound on a relatively small spool 11 so that the packages thus formed may be rotated at a speed of say 10,000 R. P. M. or higher. The rubber thread 10 is wound upon this spool in an un-twisted condition and under sufficient tension to prevent the entire mass of rubber on the spool 10 from ballooning or bulging outwardly under the high centrifugal force caused by the rapid rotation of the spool. The bare rubber thread 10 is twisted in accordance with the present invention by rotating the spool or package 11 about its longitudinal axis and by drawing the thread end-wise therefrom over one head.

In Fig. 1 the rubber thread 10 is shown as drawn downwardly from the supply spool 11 in an axial direction. In the modification of Fig. 4 it is shown as drawn upwardly from the spool 11 in an axial direction, and in the modification of Fig. 5 the thread 10 is shown as drawn horizontally from the spool 11 in an axial direction.

Referring first to the embodiment of the invention shown in Fig. 1, it will be noted that the arrangement is such that the package 11 extends downwardly from its rotating means so that the thread may be drawn downwardly therefrom. By employing this arrangement the force of gravity is utilized to help advance the thread in a general downward direction from the spool to the spinning mechanism to be described.

The spool 11 is shown as mounted upon the spindle 12 and the spool may be frictionally secured to this spindle or may be held in place thereupon by the cap 13. The spindle 12 may, if desired, be driven by a belt but is shown as driven by a small high speed electric motor 14 which motor may be secured to any suitable supporting means such as the supporting rail 15.

It is important, as above stated, to draw the thread 10 from the spool at a uniform speed so that the twist per inch imparted to this thread will be as near uniform as possible. Therefore in the embodiment of the invention shown in Fig. 1, feed means is provided below the rotating spindle 12 for pulling this thread downwardly at a definite predetermined speed. This means comprises a feed roll 16 which may be driven at any desired speed by the gear 17, and the rubber thread 10 is held in feeding engagement with this roll by the idler roll 18 which is rotatably supported between the spaced arms 19 of a swinging bracket that is pivotally mounted at 19' upon a support 20. The arrangement is such that the idler 18 rests by gravity upon the feed roll 16 and this idler may be swung upwardly away from the roll 16 to facilitate threading up of the device.

As the thread 10 unwinds from the rapidly rotating spool 11 it will tend to balloon or swing outwardly as shown in Fig. 1. This is desirable if not excessive, since it helps to get the thread away from the head of the spool, it also helps to take up slight variations in the tension of the thread as it unwinds from the spool. The size and shape of this balloon may be controlled largely by the position at which the thread guide or pigtail 21 is located below the spindle 12 in axial alignment therewith. This pigtail is preferably pivotally secured to a thread board 22 in a well known manner so that the pigtail may be swung upwardly out of the way to permit the spool 11 to be doffed. If desired the thread board 22 may be mounted for vertical adjustment upon its support 20 to thereby move the pigtail 21

toward or from the spool 11, to control the ballooning of the thread 10.

The twisted, or pre-twisted thread 10 upon leaving the feed roll 16 may have a textile cover spun thereupon substantially as disclosed in the Foster patent above cited, and the spinning mechanism employed to spin the twisted rubber thread and textile cover together to form the elastic yarn may be of the usual or well known construction. It is shown as provided with roving drafting means and a ring and traveler although a flier type of spinning means may be used.

In the construction shown the spinning mechanism is provided with the usual pairs of drafting rolls 23, 24 and 25. The covering material which is preferably a roving or rovings may be supplied to the drafting mechanism from the roving supply spindles 26. Two ends of roving 27 are shown as extending to the drafting rolls, as two ends will give a more uniform product than a single end of roving. These rovings 27 pass through the roving guide 28 supported by a bracket 29 which bracket in turn is secured to the traverse bar 30. This bar 30 as is usual is given a short traverse movement to advance the roving lengthwise of the feed rolls and thereby lessen the wear upon these rolls. It is desirable to impart a similar traverse movement to the rubber thread 10 as it passes downwardly to the nip of the drafting rolls 23 so as to bring the roving and rubber thread 10 together at the nip of these rolls. This is readily accomplished by providing a thread guide 31 upon the bracket 29 to travel therewith and which is adapted to guide the rubber thread 10 as it passes from the feed roll 16 to the nip of the rolls 23.

The spinning mechanism is shown as having the usual spinning spindle 32 which is journaled in a bearing 33 mounted upon the fixed support 34 and this spindle is shown as having the usual whirl that is driven by a belt 35 from the rotating drum 36. Upon the spindle 32 is mounted a bobbin 37 upon which the finished elastic yarn 38 is wound. The bobbin 37 as is usual rotates within an opening within the ring rail 39 which is traversed up and down in a well known manner to wind the yarn uniformly upon the bobbin 37. The ring rail 39 is provided with the usual ring 40 and traveler 41. Above the upper end of the spindle 32 is provided the thread guide or pigtail 42 carried by the thread board 43 and secured thereto by the usual hinge so that it may be thrown upwardly out of the way of the bobbin to facilitate doffing.

It is found in practice that in order to produce a balanced elastic yarn the number of windings in one direction of the covering material in one inch of the relaxed elastic yarn should be approximately equal to the number of twists of the rubber core in the opposite direction in this inch of elastic yarn. This, however, is only approximate and may vary with the size of rubber core used relative to the covering material used. Therefore when the twists of the core approximately equal the opposite winding of the cover the lower spindle 32 will be operated at about one-half of the speed of the upper spindle 12 but in the reversed direction so as to remove during the spinning operation about one-half of the twist which was previously imparted to the bare rubber core.

The take-up package 38 may be rotated in either a clockwise or contra-clockwise direction provided the let-off package 11 rotates in one direction and the take-up package 38 rotates in the opposite direction. That is the package 38

should always be rotated in a direction to reduce the twist imparted to the rubber core by the rotation of the spool 11.

Most of the spinning action which results in winding the textile cover about the rubber thread as a core takes place adjacent the discharge side of the nip rolls 23, and since the rubber core is stiffer and has a greater contractive tendency than the drafted roving the core takes the central position and the drafted fibers are wound thereabout as a cover as clearly shown in Fig. 2.

It will be seen from Fig. 1 that by operating the feed roll 16 and drafting rolls 23 at the proper speed relative to each other and to the let-off and take-up packages, the amount of twist per inch imparted to the bare rubber thread and the tension of the rubber thread between the feed roll 16 and nip of the rolls 23 may be accurately controlled. This serves to provide the proper number of twists and the proper tension of the rubber core to form a balanced elastic yarn.

Since it is contemplated that the let-off spool 11 will be operated at high speed it may be desirable to provide manually controlled brake means to 25 check rapidly the rotation of the spindle 12 after its driving power has been cut off. Therefore this spindle is shown as having a brake disc 44 about which is looped a brake band 45. One end of this band is anchored to a fixed post 46 and the other 30 end is connected by a spring to an arm 47 that projects laterally from a shaft 48 rotatably mounted in a bearing 49 and adapted to be turned slightly about its longitudinal axis to apply the 35 brake.

While the construction shown in Fig. 1 has the motor 14 for twisting the thread 10 as it is pulled off one end of the spool 11, it may be desirable in some cases to operate the various parts of the 40 machine of the present invention from a single motor so as to correlate accurately the operating speed of the spool 11, feed roll 16, drafting rolls, and spinning spindle 37. Therefore in the modified constructions of Figs. 4 and 5, the spindle for supporting the let-off package 11 is shown 45 as provided with a driving whirl instead of the driving motor 14 of Fig. 1.

In the construction shown in Fig. 4 the spool 11 of rubber thread to be twisted is mounted upon the upper end of the vertical spindle 50. This spindle is journaled in the supporting bracket 51 and may be driven by the whirl 52. Above the spindle 50 is provided the pigtail guide 53 similar to the guide 21 of Fig. 1. The rapid rotation of the spool 11 causes the thread 10 to balloon as shown, as it passes upwardly to the pigtail 53. It then passes upwardly from this pigtail to the idler roll 54 and then downwardly between the feed roll 55 and cooperating idle roll 56 which may be similar in construction and 55 operation to the rolls 16 and 18 of Fig. 1. From the roll 55 the twisted thread passes downwardly to the drafting rolls 23 to meet the drafted roving 27 and cause this roving to be spun about the thread 10 as a cover, the same as in Fig. 1.

It has been found in practice that while the 60 construction of Fig. 1 has the desirable feature of utilizing gravity to facilitate the travel of the thread from the let-off spool to the take-up package, it is open to the objection that in some cases the outer coils tend to drop down over the head of the spool as its rotation is being stopped. The up twisting construction of Fig. 4 avoids this 65 tendency.

In Fig. 5 the spool 11 of rubber thread is mounted upon a horizontal spindle 57 having the oper-

ating whirl 58, and the thread 10 upon leaving this spool passes through the guide 59 and then about an idler 60. From this idler it is pulled downwardly by the feed roll 61 and idler 62. From this point on the operation is the same as 5 in Fig. 4.

In the construction shown in Figs. 4 and 5 it is contemplated that the let-off and take-up spindles and various feed rolls will all be driven from the same source of power so that the speed ratio 10 between these parts will remain constant.

It will be apparent from the foregoing that as a result of the apparatus and method of the present invention the rubber thread that is to form the core of the elastic yarn is pre-twisted in one 15 direction and is then subjected to a spinning operation which removes part of this twist as the covering material is spun thereupon in the opposite direction, and that these operations are carried out simultaneously and continuously as the 20 rubber thread travels from the let-off package 11 to the take-up package 38.

In order that the elastic yarn herein contemplated may be further understood the following 25 tables are given as illustrating a few of the many constructions that may be made by employing the method and apparatus of the present invention.

Tables of construction

	I	30
1. Gauge of round rubber core, relaxed...	125'S	
2. Elastic yarn, relaxed... yards per lb...	11,000

While the covering for the elastic yarn shown

in Fig. 2 is preferably formed of a drafted roving or rovings, it is contemplated that the method and apparatus of the present invention may be employed to apply a textile yarn or other form 5 of strand about the rubber thread as a cover. Through the present invention it is possible to produce an elastic yarn which is well balanced and in which the helical windings of the drafted roving blend together to form a soft smooth cover 10 that closely resembles ordinary textile yarn in feel and appearance.

Having thus described our invention, what we claim and desire to protect by Letters Patent is:

1. The method of making a balanced elastic 15 yarn having a twisted rubber core and a textile cover spun thereupon, which consists in rotating a package of bare rubber thread and pulling the thread endwise therefrom to twist it in one direction, and advancing this thread as it is twisted 20 and a textile roving towards spinning means to thereby spin said roving about the core in the opposite direction so as to form a helical cover upon the core adapted to balance the twist of the core and hold it stretched.

25 2. The method of making an elastic yarn having a twisted rubber core and a cover spun thereupon in the opposite direction, which consists in rotating a package of rubber thread and pulling the thread endwise therefrom to twist it in one 30 direction, and advancing this thread as it is twisted and a covering strand towards spinning means to thereby spin said strand about the core in the opposite direction so as to wind it about the core as a cover and reduce the twist of said 35 core.

3. The method of making an elastic yarn having a twisted rubber core and a cover spun thereupon in the opposite direction, which consists in rotating a package of rubber thread and pulling 40 the thread endwise therefrom in a downward direction to twist it in one direction and advance this thread in a downward direction as it is twisted towards spinning means, feeding a covering strand also towards said spinning means to thereby spin this strand about the core in the opposite 45 direction to wind it about the core as a cover.

4. The method of making an elastic yarn having a twisted rubber core and a cover spun thereupon in the opposite direction, which consists in 50 rotating a package of rubber thread and pulling the thread endwise therefrom to twist it in one direction, advancing the thread as it is twisted towards spinning means and simultaneously stretching it a predetermined amount, feeding a covering strand also towards said spinning means 55 to thereby spin this strand about the core in the opposite direction to wind it about the core as a cover.

5. The method of making an elastic yarn having a twisted rubber core and a cover spun thereupon in the opposite direction, which consists in rotating a let-off package of rubber thread and pulling the thread downwardly therefrom to twist 5 the thread and utilize the force of gravity in removing the thread from said package, simultaneously rotating the take-up package of spinning means for this thread in a direction to reduce the twist of this thread as it is wound on said 10 take-up package, and delivering a covering strand to said spinning means so as to spin it about said thread as a cover.

6. The method of making an elastic yarn having a twisted rubber core and a cover spun thereupon in the opposite direction, which consists in 15 rotating a let-off package of rubber thread and pulling the thread downwardly therefrom to twist the thread and utilize the force of gravity in removing the thread from said package, simultaneously rotating the take-up package of spinning means for this thread in a direction to reduce 20 the twist of this thread as it is wound on said take-up package, delivering a covering strand to said spinning means so as to spin it about said 25 thread as a cover and controlling the stretch of said rubber thread as it is delivered to said spinning means.

7. The method of making an elastic yarn having a twisted and tensioned rubber core and a 30 cover spun thereupon, which consists in rotating a package of rubber thread and pulling the thread endwise therefrom at a uniform rate of speed to twist it in one direction, advancing this thread as it is twisted at another point at a different 35 uniform speed to thereby tension the thread a predetermined amount and feed it towards spinning means, delivering a covering strand also towards said feeding means to thereby spin said strand about the core in the opposite direction 40 so as to wind it about the core as a cover.

8. The method of making an elastic yarn having a twisted rubber core and a cover of textile fibers spun thereupon in the opposite direction, which consists in rotating a package of rubber 45 thread and pulling the thread endwise therefrom in a downward direction to twist it, drafting unspun textile fibers and advancing them towards spinning means, and advancing said thread as it is twisted towards said spinning means to thereby spin the textile fibers about the core in an opposite direction to wind it thereupon as a 50 cover.
